C. S. SANDERS

HAIR PRESSING CAP

Filed March 16, 1923

C. S. SANDERS.

Inventor,

By *Sterling P. Buck,*
Attorney.

UNITED STATES PATENT OFFICE.

CHARLES S. SANDERS, OF BALTIMORE, MARYLAND.

HAIR-PRESSING CAP.

Application filed March 16, 1923. Serial No. 625,609.

To all whom it may concern:

Be it known that I, CHARLES S. SANDERS, a citizen of the United States, residing at 417 West Hoffman St., Baltimore city, State 5 of Maryland, have invented certain new and useful Improvements in Hair-Pressing Caps, of which the following is a specification.

This invention relates to head-gear, and especially to a hair pressing cap for use by 10 individuals or by professional hair-dressers.

One object of this invention is to provide a very convenient, ornamental, neat, practical and effective cap that automatically conforms to the horizontal circumferences or 15 peripheries of heads of various sizes and shapes so as to bind and press the hair against the scalp for securing the hair in whatever shape and position it has been arranged, and to assist the hair in becoming 20 set to the desired position or shape.

A further object of the invention is to provide a cap of this character which is of comparatively simple construction, formed of few parts, and comparatively inexpensive 25 to manufacture.

Other objects and advantages will be pointed out or implied in the following details of description, in connection with the accompanying drawings in which, Fig. 1 is 30 a tilted side view of a cap formed in accordance with my invention, a part of the lining being removed from its interior to show the connection of one of its opposite elastic elements or sheets; Fig. 2 is a tilted 35 end view; Fig. 3 is an enlarged and exaggerated sectional view, the section being along the line 3—3 of Fig. 1.

Referring to these drawings in detail, in 40 which similar reference characters refer to similar parts throughout the several views: The cap preferably comprises an outer fabric 1 and an inner fabric or lining 2, preferably both of silk or satin, and a binding strip 3 is stitched to the parts 1 and 2 and 45 secures their lower edges together, as shown. The cap is also preferably formed in two primarily separate sections, or provided with a median seam 4 which unites the primarily 50 separate halves of its inner and outer fabrics.

Elastic elements or sheets of rubber or 55 combined rubber and fabric are shown at 5, these being inserted between the inner and outer fabrics at opposite sides of the cap, or at opposite sides of the median seam 4

which latter extends in the vertical median plane from front to rear of the cap. The vertical edges of the elastic sheets are stitched at 6, preferably with double rows of stitching, and this stitching 6 extends 60 through the inner and outer fabrics as well as through the elastic elements. A row of stitching 7 may also extend horizontally from the stitchings 6 of each pair which secure the opposite ends of each elastic or 65 retractile element 5 to the inner and outer fabrics; but the stitching 7 is made before the folds 8 are formed, these folds being formed by the retraction of the elastic elements, or by any appropriate means for permitting the elastic elements to be stretched or extended in the horizontal direction or along the line 3—3. It should be understood 70 that the elastic elements have their upper and lower edges free, being between the stitching 7 and that which holds the binding 75 in place.

From the foregoing, it may be seen that the lower periphery of the cap can be stretched so as to fit much larger heads than 80 it fits when contracted, and that when it has been adjusted on any head larger than its minimum periphery, it automatically retracts and conforms to the horizontal periphery of the head. This contraction 85 takes effect also in the horizontal central part of the cap, as well as in its lower part, in view of the fact that the elastic sheets extend up to said horizontal central part or plane. The median seam 4 serves as a 90 guide for placing the elastic parts of the cap on corresponding parts of opposite sides of a person's head, so that a substantially 95 equal pressure is exerted on these corresponding parts, and the hair on the opposite sides of the head is pressed alike.

Apertures or vents 9 are formed through the fabrics 1 and 2, in registering pairs, and circular series of stitches 10 are arranged around these vents and serve as ornaments, as bindings for the vents, and as means to unite the inner and outer linings 100 at spaced intervals throughout the cap.

It is not intended to limit this invention to the exact construction and arrangement here shown, but changes may be made within the scope of the inventive idea as implied and claimed.

What I claim as my invention is:

1. The hair-pressing cap which includes 110

a crown formed of an outer fabric and an inner fabric, and two elastic sheets between and secured to the outer and inner fabrics at opposite sides of the cap, the inner and outer fabrics being provided with puckers or folds at the elastic sheets to permit these opposite sides to be expanded and contracted, said elastic sheets being effective to cause the contraction of these sides for the purpose of holding and pressing the hair of the wearer.

2. The hair-pressing cap which includes a median seam extending from front to rear, also including inner and outer fabrics each provided with normally folded portions, and two sheets of elastic material between the outer and inner fabrics at points in a vertical plane which intersects said seam at its middle, the vertical edges of

these elastic sheets being secured to said inner and outer fabrics while the upper and lower edges are free and extend between said folded portions, substantially as described and shown, for the purpose specified.

3. The hair-pressing cap which includes a crown formed of an outer fabric and an inner fabric, and an elastic sheet between and secured to the outer and inner fabrics at one side of the cap, the inner and outer fabrics being provided with puckers or folds at the elastic sheet to permit this side to be expanded and contracted, said elastic sheet being effective to cause the contraction of the sides for the purpose of holding and pressing the hair of the wearer.

In testimony whereof I affix my signature.

CHARLES S. SANDERS.
